BLANK-FORMING METHOD AND MECHANISM FOR ENVELOPE MAKING MACHINES

Vincent E. Heywood, Worcester, Mass., assignor to United States Envelope Company, Springfield, Mass., a corporation of Maine

Application July 2, 1948, Serial No. 36,776

19 Claims. (Cl. 164—61)

This invention relates to the production, by successive cut-offs, made crosswise on an advancing paper web supply, of substantially rhombic or diamond-shaped envelope blanks, for direct passage, one after another, to and through the flap folding and glue applying instrumentalities of an envelope making machine.

In all such envelope manufacture directly from a paper web supply, the successively severed rhombic pieces or blanks must undergo a straightaway movement, corresponding corners foremost, at an angle to the direction of web travel. This arises from the need of said blanks to pass through said flap folding and glue applying instrumentalities in exact symmetrical relation to the latter's fixed centerline. These requirements, heretofore, have imposed severe handicaps and difficulties, on the use and handling, in this web cut-off method of envelope blank formation, of webs of various widths, for the production of these rhombic blanks in a wide range of sizes and length-to-width ratios.

My invention, as hereinafter described, overcomes all such difficulties and handicaps. This is achieved by providing for correlated angular adjustments (1) of the direction of web feed and (2) of the obliquity of the web cut-off—both about a vertical axis in the aforesaid fixed centerline of straightaway blank movement. Thereby the cut-off square or diamond-shaped pieces, whatever be their sizes and length-to-width ratios, can always be presented and forwarded in the required centralized symmetrical relation, not only to the envelope machine's aforesaid flap folding and glue applying instrumentalities, but also, in advance thereof, to suitably adjustable blank scoring, trimming and notching devices arranged along said fixed centerline.

With the above and other objects in view, the invention comprises the several steps, sequences, devices, combinations, and arrangements of parts hereinafter set forth and illustrated in the accompanying drawings, from which the several features of the invention and the advantages attained thereby will be readily understood.

In the accompanying drawings:

Fig. 1 is a fragmentary side view of certain portions of an envelope machine of the web supply type, in which the present invention is incorporated;

Fig. 2 is a plan view, partly in horizontal section, of the machine portions shown in Fig. 1, the section being taken substantially on the line 2—2 of Fig. 1;

Fig. 3 is a side elevation partly in vertical section, of the right-hand parts of Figs. 1 and 2, the section being taken substantially along the line 3—3 of Fig. 2;

Fig. 4 represents a fragmentary horizontal sectional view, the section being taken substantially along the line 4—4 of Fig. 3;

Fig. 5 represents a fragmentary vertical sectional view, the section being taken substantially along the line 5—5 of Fig. 3;

Fig. 6 represents a fragmentary vertical sectional view, showing two pairs of web feeding rollers, the section being taken substantially along the line 6—6 of Fig. 2, but omitting the parts between said pairs of rollers;

Fig. 7 represents a transverse vertical sectional view of the web-severing means, the section being taken substantially along the line 7—7 of Fig. 2;

Fig. 8 represents, on an enlarged scale, a fragmentary cross sectional view of the web-severing means, the section being taken substantially along the line 8—8 of Fig. 7;

Fig. 9 is a diagrammatic view illustrating the suc-

2

sive steps performed by the invention in the production of successive envelope blanks from a continuous web of material, and showing the adaptability of the invention to webs of various widths;

Fig. 10 is a diagrammatic view, on a scale smaller than that employed in Fig. 9, illustrating the subsequent successive steps employed in the manufacture of completed envelopes from such blanks, it being understood that the steps illustrated in this figure are performed by mechanisms with which the present invention is not concerned;

Fig. 11 represents a vertical sectional view substantially on line 11—11 of Fig. 1, of the blank trimming and scoring mechanism, in a different condition of adjustment from that shown by Fig. 2;

Fig. 12 represents a top plan view of the so-adjusted mechanism, and showing sectionally, on line 12—12 of Fig. 14, the direction-changing mechanism for the severed blanks;

Fig. 13 represents a fragmentary right-hand end view from the plane of the line 13—13, Fig. 11 of the mechanism which is disclosed in Fig. 11;

Fig. 14 represents a fragmentary vertical sectional view of portions of said mechanism, the section being taken substantially along the line 14—14 of Fig. 11;

Fig. 15 represents a top plan view of the blank notching mechanism;

Fig. 16 represents a vertical sectional view substantially on line 16—16, Fig. 2, showing the notching mechanism illustrated in Fig. 15;

Fig. 17 represents a fragmentary sectional view of the notching mechanism, the section being taken substantially along the line 17—17 of Fig. 16;

Fig. 18 represents another fragmentary sectional view of the notching mechanism, the section being taken substantially along the line 18—18 of Fig. 16;

Fig. 19 represents a detached end view, partly in section, of the supporting stand for the supply roll from which the web material, as shown in Figs. 1 and 3, is drawn;

Fig. 20 is a fragmentary side elevational view of the supporting stand shown in Fig. 19; and

Fig. 21 is a sectional view of the parts shown in Fig. 20, the section being taken substantially along line 21—21 of Fig. 20.

Like reference characters refer to like parts in the different figures.

General purpose of the mechanism

Referring first to Figs. 9 and 10, it is to be understood that the present mechanism is adapted to draw from a supply roll (see 47, Figs. 1 and 3) a continuous web of paper, the forward end of such a web being indicated in Fig. 9 by the numeral 18. The present mechanism provides appropriate means for continuously feeding the web of material in the general direction of arrow 18 and past a web-severing means which functions at regular intervals to sever the traveling web 18 on an oblique line such as 19, Fig. 9, thereby to form a succession of individual unconnected pieces each of diamond or rhombus shape, for conversion by subsequent notching and trimming into envelope blanks 20, 20. Following severance of each diamond-shaped piece from the continuous web 18, the present invention contemplates the action thereon of feeding means adapted to convey the individual pieces, for such notching and scoring operations, away from the severing means in a straightaway path (see arrows) whose centerline 21 parallels the fold lines (25, 25) of each blank's side flaps. Thus said feeding means so alters the direction of travel of the material, that the successive substantially diamond-shaped blanks 20, 20 travel in a path which intersects the web path at an angle 22 which is always equal to the angle 23 made by each fold line 25 with the blank's obliquely-disposed sides.

As hereinafter described, the present invention contemplates the provision of means whereby each blank's side flap apexes are trimmed off, as shown at 24, 24, accompanied by scoring of each blank along the lines 25, 25. Means are also provided for notching each blank at locations 26, 26 after it has been scored and trimmed. Thereafter each blank advancing along said centerline 21 in symmetrical relation thereto is notched again at locations 27, 27. After the above stated operations have

been performed, the so-completed individual envelope blanks are forwarded along and symmetrically to said centerline 21 to other portions, not shown, of the envelope making equipment, which may operate, conventionally or otherwise, in the sequence shown from right to left in Fig. 10, to fold over the side flaps 28, 28 of each blank and thereafter to apply a gum area 29 upon the bottom flap 30 preparatory to folding over this flap 30 upon the side or end flaps 28, 28. In subsequent operations, the seal flap 31 may have a gummed area 31' applied thereto thus completing the envelope. However, as previously noted, the devices required for performing the envelope making operations indicated diagrammatically by Fig. 10, form of themselves no part of the present invention and thus are not disclosed and described herein.

Power drive mechanism

The operative parts of the present mechanism are mounted on a horizontal table 32 providing a support surface of the generally angular shape of Fig. 2. The drive of the mechanism is from any suitable source such as an electric motor 33 located beneath the table 32. Appropriate means, not herein illustrated, are provided for connecting the motor 33 with a gear 34 the latter serving for the drive of vertically and horizontally disposed shafts 35 and 36, respectively, through the medium of gear 37 and shaft extension 38 which is connected to gear 34. As shown in Figs. 1 and 2, the vertically disposed shaft 35 drives a train of gears 39 through a bevel gear 40 fastened upon the shaft 35 and meshing with a second bevel gear 40' attached to one of the gears 39' of the gear train 39. This train of gears 39 powers certain of the mechanisms of the present invention which will be hereinafter described.

Referring particularly to Figs. 1 and 2, it will be seen that the horizontally disposed shaft 36 extends along one side of the table 32 and is operatively connected with a cross shaft 41 by means of a pair of bevel gears 41', 41'. Referring to Fig. 7, it will be seen that the shaft 41 extends beneath the table 32 and serves to drive a vertically disposed shaft 42 by means of a pair of bevel gears 43, 43. At the lower end of the vertically disposed shaft 42 is secured a drive gear 44 which meshes with a driven gear 45 (see Figs. 1 and 3). Thus, rotation of the main shaft 36 will cause rotation of the drive gear 44 through the intermediate shafts 41 and 42. Referring particularly to Figs. 1 and 3, it will be seen that driven gear 45 is carried upon the lower end of a vertically disposed shaft 46 which serves, as hereinafter described, to actuate the web feeding mechanism.

Web feeding mechanism

The continuous web 18, as indicated in Fig. 3, is taken from a supply roll 47 and is continuously drawn down between a pair of guide rolls 48, 48 having suitable bearings in horizontally spaced upright side frames 49 and 50. The latter extend upwardly from a swivel plate 51 which overlies and rests upon the right-hand divergent portion (Fig. 2) of table 32 and is arranged for angular adjustment thereon about a vertical axis, as hereinafter described. The supply roll 47 is journaled in a stand comprising a pair of spaced saddle members 52 and 53 which are respectively mounted upon the side frames 49 and 50. (See Figs. 1, 3, 5 and 19.)

From the guide rolls 48, 48 the continuous web 18 passes downwardly around a power driven roll 54 which is also suitably journaled in the frames 49 and 50 (see Figs. 2 and 3). Thereafter, the web passes over an idler roll 55 and is looped around a driven feed roll 56, before passing reversely between the latter and a cooperating feed roll 57. (See Figs. 2, 3 and 5.) As shown in Figs. 3 and 5, the power driven feed rolls 56 and 57 are appropriately journaled in the side frames 49 and 50 as is also an overlying power driven shaft 58, for cooperation with the roll 57. Referring particularly to Fig. 5, it will be seen that the shaft 58 is provided with a pair of spaced roll elements 59 and 59' for engaging the web's edges. Beyond these power driven rolls, the web passes in a left-hand direction, as viewed in Fig. 3, to the web-severing means which will be more fully described hereinafter. Roll element 59' is adapted to be adjusted toward and away from roll element 59 in order to accommodate the machine to different widths of webs. As will be hereinafter more fully described, roll element 59 is adapted to remain in a fixed position on shaft 58, since all webs, re-

gardless of width, are so positioned in the machine that one edge (line 72 or 72a, Figs. 5 and 9) always coincides with the outer edge of this fixed roll element 59.

All of the above mentioned power driven feed rolls 56, 57, 58, 59, 59' are actuated from the vertically disposed shaft 46 which is illustrated in Fig. 3. This shaft 46 is appropriately journaled within a frame element 60 which extends downwardly from side frame 49 through suitable openings in the swivel plate 51 and the table 32. The upper portion of the shaft 46 has secured thereon a worm wheel 61 which meshes (see Fig. 4) with a worm gear 62. The worm gear 62 is mounted upon a horizontally projecting stub shaft 63 whose outer end carries a replaceable change-speed gear 64 (see Figs. 3 and 4) adapted through a specially-mounted idler gear 65, to drive a gear 66 on the shaft of the web feeding roll 57. Thus, rotation of the vertically disposed shaft 46 serves to rotate the feed roller 57 which, in turn, drives its adjacently disposed cooperating feed rolls 56 and 58 due to the fact that each of these rolls is operatively connected with the roll 57 by means of the gears 66, 67 and 68 carried upon their end portions, as indicated in Figs. 3 and 5. The roll 54 is also driven from the roll 57 through the medium of idler gears 69, 69' and 70 secured to shafts which are appropriately mounted in the side frame member 49 as shown in Figs. 2 and 3, the gear 70 meshing with a gear 54' which is fast on the shaft of roll 54.

Referring to Figs. 3 and 5, the present mechanism provides a hand lever 75 by which to raise the roll elements 59 and 59' off of the shaft 58 so as to facilitate the initial threading of the paper web through the power driven feed rolls. More specifically, the lever 75 is pivoted upon a pin 76 carried by the frame element 49 and the lower end portion of the lever is attached to a horizontally disposed bar 78, which is slidably mounted within the oppositely disposed frame elements 49 and 50, and passes through a pair of blocks 79 and 80 which are suitably mounted for vertical movement within the frame elements 49 and 50. Each of these blocks 79 and 80 is spring biased downwardly in a manner such that the gear 68 of the shaft 58 is in proper mesh with the gear 66 of the feed roll 57. However, it will be understood that whenever the lever 75 is pushed inwardly toward the saddle 52, it will lift slightly each of the blocks due to the fact that the blocks are provided with depending pins 81 which engage appropriate notches 82, 82 of the bar 78. Furthermore, whenever the blocks are so elevated, they will similarly lift the shaft 58 and thus permit the paper web to be inserted, with facility, between the roll elements 59 and 59' and the feed roll 57. A lever 83, Fig. 1, is similarly associated with the feed roll 56, to withdraw the latter, temporarily, from contact with roll 57, so as to facilitate the introduction of the web to the feeding devices.

Beyond the cooperating feed roll 57 and roll elements 59, 59', the web 18, travelling horizontally as shown in Fig. 3, is engaged by a pair of feeding rolls 84 and 85. The rolls 84 and 85 are mounted respectively upon vertically spaced and horizontally disposed shafts 86 and 87 respectively, which are suitably journaled in a housing element 88 carried by the side frame member 49. Within the housing 88, the shafts 86 and 87 are provided with intermeshing gears 89, 89 providing for synchronized rotation of the feed rolls. As shown in Figs. 1 and 2, the lower shaft 87 extends out of the housing 88 and into a gear box 90 wherein it is connected to a power shaft 90' by means of a pair of bevel gears 91, 91. Referring to Figs. 1 and 2, it will be noted that the gear boxes 88 and 90, like the other parts of the web feeding mechanism, are suitably carried directly upon the swivel plate 51. This power shaft 90' extends along one side of the web feed mechanism and into a second gear box 92 mounted directly upon the side frame element 49. Within this gear box 92 the power shaft 90' is provided with a bevel gear 93 which meshes with a similar bevel gear 94 carried upon the shaft of the feed roller 57. (See Figs. 2 and 5.) Thus, it will be manifest that the feeding rolls 84 and 85 will be driven in synchronism with the above described web feeding elements.

As shown in Figs. 2 and 3, the power shaft 90' extends also in the other direction from the gear box 90 and into a third gear box 95 which is also suitably mounted directly upon the swivel plate 51. Within the gear box 95 the shaft 90' is connected with a shaft 96 by means of suitable bevel gears 97, 97. (See Fig. 2.)

Referring particularly to Figs. 2 and 3, it is to be seen that the shaft 96 extends into a housing 98 also suitably carried upon the swivel plate 51. This housing contains a second shaft 99 (see Fig. 3) which is connected to the shaft 96 by means of suitable intermeshing gears 100, 100. It should be noted that both the gear box 95 and the housing 98 are omitted from Fig. 1 so that other elements of the mechanism may be shown more clearly.

The shafts 96 and 99 carry cooperating roller elements 101 and 102 which (see Fig. 2) are operative on and coincide with the same web edge (line 72 or 72a; Figs. 5 and 9) as the fixed or nonadjustable roller element 59 of shaft 58. According to my invention, each paper web, in its horizontal travel between the feed rolls 84, 85 and 101, 102, is severed obliquely at regular intervals, by a web severing mechanism, designated as a whole by the numeral 103 (Figs. 3 and 7), which will now be described.

Web-severing mechanism

The web-severing mechanism includes a base member 104 which (see Fig. 2) extends across the table 32 substantially at the juncture of the latter's two angularly related portions. As shown in Fig. 7, the table 32 is apertured in this vicinity for the vertical shaft 42, whose bearings are mounted in a suitable sleeve member 42a, having an annular collar 105 concentric with shaft 42, and by which it is secured to the table 32. The base member 104 seats on collar 105 and on a pad or plate 106 of the same thickness, near the other side of table 32. The base member 104 provides a head or frame portion 107 in which is rotatably mounted a horizontal knife-carrying shaft 108. The right-hand end (Fig. 7) of the shaft 108 carries a gear 109 which meshes with a similar gear 110 carried by a countershaft 111 which is suitably journaled in base member 104. The inner end of the countershaft 111 carries a bevel gear 112 which meshes with a similar gear 113 on the upper end of shaft 42 whereby the latter's rotation serves, through the above described gearing, to drive the knife-carrying shaft 108, in timed relation to the feed of the web material.

As shown in Fig. 8, the shaft 108 has a flat surface 114 against which is firmly seated, as by means of a plurality of screws 115, 115, an elongated knife blade 116. Standing at right angles to the flat surface 114 is an abutment 117 which serves as a backing for the blade 116. This abutment carries a plurality of adjusting screws 118 by which to move the blade into proper alignment with a cooperating stationary ledger blade 119 which is supported, above the travelling web 18, upon a block 120 secured to a bridge piece 121 that connects the opposite ends of the frame or head portion 107. This stationary blade is here shown as an elongated flat member which is secured to the block 120 by a plurality of bolts 122, 122. Suitable adjusting screws 123, 123 are provided in said block for moving the stationary blade 119 into proper web cutting position relative to the rotary blade 116. It has been found that by setting the stationary ledger blade 119 slightly out of parallel with the rotary knife 116, a scissors-like cutting action on the web may be obtained. Such an adjustment reduces the cutting load and also reduces the amount of shock imparted to the knives.

The rotary and stationary blades of the web-severing mechanism extend obliquely across the paper web, so that at each rotation of the knife-carrying shaft 108 the moving web 18 will be severed along an oblique line (see 19, Fig. 9) thereby to form a succession of identical diamond-shaped pieces. In the present mechanism, the blade 116 is driven at an appropriate constant speed. Thus, for each width of web material which is handled, there must be chosen and imparted a rate of linear feeding speed compatible with the cut-off, by blade 116, of diamond-shaped pieces which in every case, as shown by Fig. 9, are normal to and symmetrical with the fixed direction line 21 of subsequent blank travel through the machine.

In order to obtain the above-mentioned range of speed changes for the web feed, the shaft which carries idler gear 65 projects from a plate or bracket 73 (Figs. 2, 3 and 5) said plate having a pivotal mounting, for angular adjustment, upon an extension of roll 57, which is concentric with the axis of the driven gear 66, in mesh

with said idler 65. Said plate 73 provides an arcuate slot (Fig. 3) for passage of a suitable bolt 74, by which to fix the idler gear 65 in that angular position which obtains its proper mesh with the selected size of driving gear 64 that is secured to the shaft 63; it being understood that, for such change speed purposes, a plurality of sizes of such driving gears 64 are provided, to take care of the different feeding speed requirements of different widths of webs.

- 10 The vertical shaft 42 is journaled at its upper end in a bearing 124 whose upper outer peripheral portion as shown in Fig. 7 is snugly surrounded by an aperture 125 of the base member 104. Thus, the web-severing mechanism as a unit is angularly adjustable about the vertical axis (see a, Figs. 2 and 9) of the shaft 42 to vary the obliquity of the cut-off by blade 116, for different widths of webs. As shown in Fig. 2, the base member 104 is appropriately slotted, to receive bolts 126, 126 by which to clamp the web-severing mechanism in any desired angular position upon the right-hand divergent portion of the stationary table 32. For convenience, the stationary pad 106 and the base member 104 are each provided with suitable indicia so that an operator may accurately adjust the web-severing mechanism to the correct 20 obliquity for any particular width of web.

Angular adjustment of web feeding mechanism

As previously pointed out, each diamond-shaped piece, upon severance from the forward end of the moving web 30 material, is moved in a new direction (line 21, Fig. 9) that prevails thereafter throughout the machine, for the several blank-completing and envelope-fabricating operations shown by Figs. 9 and 10. The need for every such obliquely-severed piece, regardless of its length or width 35 dimensions, to extend at right angles to and in complete symmetry with said direction line 21, makes it compulsory for an edge (72, Figs. 5 and 9) of any moving web that is being handled, to intersect at all times with the vertical axis a (of shaft 42) about which the web-severing mechanism, as above described, is angularly adjustable. Otherwise, the required symmetrical relation of the obliquely severed material to the line 21 would not be achieved.

45 My invention obtains and preserves this intersecting relationship (of web edge with vertical axis a) under all conditions encountered in the handling of webs of different widths, by providing for angular adjustment of the entire web-feeding mechanism about said axis a. To this end, as shown in Figs. 2 and 7, the swivel plate 50 51, which carries the entire web feeding mechanism, has a circular aperture 127 which snugly and concentrically surrounds the collar 105, concentric with shaft 42, that projects upwardly from the surface of table 32. From this, it will be understood that the 55 web feeding mechanism and the web-severing mechanism are both angularly adjustable, relative to each other, about the same vertical axis a. As shown in Fig. 2, the other end of the swivel plate 51 is appropriately slotted to receive bolts 128, 128 adapted to clamp the entire web feeding mechanism in any desired position of angular adjustment on table 32. For convenience, the table 32 carries a stationary calibrated plate 129 having appropriate indicia by which to facilitate the accurate angular adjustment of the swivel plate 60 65 51 on said table.

65 By angularly adjusting the web-severing mechanism, as well as the web feeding mechanism, both about the axis a of vertical shaft 42, the apparatus is readily adaptable to the handling of webs of various widths, for the production of a wide range of sizes of diamond-shaped envelope pieces. Every such web, regardless of its width, is so fed that its edge (72, Figs. 5 and 9) always intersects the vertical axis a of the shaft 42. Such a condition must prevail in order for the respective angular adjustments of the web-severing and web feeding mechanisms to have their desired effect.

This is illustrated by the broken line showing of Fig. 9, depicting how the handling of a narrower web 18a (to produce smaller diamond-shaped pieces 29a for conversion into smaller blanks) requires, from the settings for the larger pieces that become the blanks 20, a clockwise angular adjustment of the entire web feed (by swivel plate 51) and a counterclockwise angular adjustment of the web severing mechanism 103, to a 80 85 location for producing the line of severance 19a. Both

of these adjustments are about the aforesaid vertical axis *a*, which has to be intersected in the case of every web, regardless of width, by said web's marginal edge (see 72 and 72a, Fig. 9) in order to obtain the proper relation and symmetry of the successive cut-off pieces with the center line 21 of their ensuing movement through the machine.

Transverse adjustment of web supply roll

The supporting members 52, 53 of supply roll 47 extend upwardly (see Figs. 1, 3, 5 and 19) from the side frames 49 and 50, which are mounted upon and secured to the swivel plate 51. Thus the web supply roll is part and parcel of the web feeding mechanism, and partakes of the latter's angular adjustments, as a unit, about the vertical axis *a*, in setting up and adjusting the mechanism for production of any desired size of diamond-shaped pieces, within the range of the web widths that can be handled. Such setting up operation, for any particular width of web, involves as heretofore described, an accurate positioning of the web, transversely of the feeding mechanism, to maintain register of its proximate edge (72 or 72a, Figs. 5 and 9) with the outer edge of fixed roll element 59 and also, as shown in Fig. 2, with the outer edges of the subsequent feed rolls 101, 102. The vertical axis *a* intersects a line through these roll edges, the latter thus constituting a datum point or line to which the proximate edge of every web, regardless of width, must be adjusted, and at which said edge must be maintained.

For this purpose each web supply roll 47 is arranged for adjustment, transversely of the web feeding mechanism, in the manner shown by Figs. 19, 20 and 21. That is, each supply roll 47 is mounted upon a shaft 187 between a pair of spaced collars 188 and 189. Each of the collars 188 and 189 carries a ball bearing 190, the latter's outer races being receivable within arcuate grooves 191, 191 formed in a pair of saddle blocks 192 and 193, associated respectively with the support members 52 and 53. Saddle block 192 is attached to a cross slide 194 which is slidably mounted upon the top of the member 52 in a conventional manner, as shown in Figs. 20 and 21, and saddle block 193 has a similar mounting upon member 53. A horizontal shaft 195, having threaded engagement with the member 52, passes through a boss 196 of the cross slide 194, and carries a collar 197, which prevents longitudinal movement of the shaft relative to said cross slide. The outer end of shaft 195 carries a hand wheel 71 which the operator turns, in one direction or the other, to shift the supply roll transversely of the web feed mechanism, so as to establish, and to maintain during operation of the machine, the necessary registration of the web's proximate edge with the aforesaid datum line through the outer roll edges (of 59 and 101, 102) and the vertical axis *a*, in all selected angular adjustments, about said axis, of the web feeding and web severing mechanisms.

Direction-changing mechanism for severed material

One of the final edge-engaging rolls 101, 102 of the web feeding mechanism (for example the roll 102, see Fig. 6) is circumferentially relieved or cut away, as shown at 130. The length and angular position of this relieved or non-feeding portion 130 is appropriately related and coordinated, not only with the operations of the web-severing mechanism 103, but also with the action of two pairs of direction-changing rolls 131, 132, whose axes (see Figs. 2 and 12) stand at right angles to the center line (21) of each severed piece's subsequent movement through the machine. Said pairs of rolls 131, 132 are on opposite sides of said center line, and have relieved or cut-away portions 131', 132' (see Fig. 13) which permit the end of the traveling web material, prior to each severing operation, to enter freely, without obstruction or interference, between them, as shown in Figs. 2 and 12. Immediately after each severing operation, the resulting diamond shaped piece, released from rolls 101, 102 by the latter's non-feeding portion 130, becomes subject to the feeding or unrelieved portions of rollers 131, 132, and is by them moved rapidly away, in the direction shown by center line 21.

The two pairs of rolls 131, 132 are carried by the opposite ends of a pair of vertically spaced shafts 133 and 134 (Figs. 12 and 13) which are journaled respec-

tively in suitable housings 135 and 136. As shown in Figs. 12 and 14, housings 135 and 136 derive partial support, and their roll shafts 133 and 134 derive rotation, from respective rotary parallel shafts 137 and 138, which are vertically spaced from each other and suitably journaled in laterally spaced frame elements 139 and 140 that extend upwardly from opposite sides of the left-hand straight-away portion (Fig. 2) of table 32. The shafts 137 and 138 are rotated in unison by means of intermeshing gears 141, 141 at the end of the gear train 39.

One end of the upper housing 135 encircles the rotary shaft 137, and its other end carries a plate 142 which overhangs, and bears against a plate 143 projecting horizontally from the web-severing mechanism 103, thereby to support said housing in a horizontal position, (see Figs. 12, 13 and 14). As shown in Fig. 12, the housing 135 contains a driving gear 144 secured to the shaft 137. This gear 144 imparts rotation to the upper rolls 131, 131 through an idler gear 145 and a gear 146 on the shaft 133 of said upper rolls 131, 131. The lower housing 136 has a similar mounting on the lower rotary shaft 138 and contains a driving gear 147 of said shaft which imparts rotation to the lower rolls 132, 132 through an idler gear 148 and a driven gear 149 on the lower roll shaft 134. The lower housing 136 is supported in horizontal position by an attached pad 150, the latter adapted to bear against any underlying projection, not shown, of table 32. The pad 150 and plate 142 carry suitable adjusting screws 151, 151, by which to position the housings 135, 136 at the proper levels for the operation of their respective rolls 131, 132.

The rotary shafts 137 and 138 thus drive the direction-changing rolls 131, 132 in synchronism, for seizing each piece, as soon as it is severed from the web, and for initiating its leftward movement (Figs. 2, 9 and 12) in the direction of, and in symmetrical relation to the line 21. Such blank movement is continued, throughout the fixed straight-way portion (Figs. 1 and 2) of the machine, by successive pairs of upper and lower rollers, on axes normal to line 21, such as the wheels or rollers 152, 153 on the rotary shafts 137 and 138 respectively.

Adjustable blank scoring and trimming mechanism

The rotary shafts 137 and 138 also provide the devices by which the successive pieces, moving in the direction of line 21, have their apex portions trimmed off, as shown at 24, 24, Fig. 9, and are also scored along the lines 25, 25 defining the folds of the resulting blanks' side flaps 28, 28. For so scoring the blanks, the upper shaft 137, on opposite sides of and equidistant from the center line 21, carries a pair of scoring disks 154, 154, each cooperating with a hardened cylinder 155 on the lower shaft 138. For so trimming the blanks, the upper shaft 137 beyond each scoring disk 154, is equipped with suitable cutting-off or trimming blade 156, said two blades cooperating with hardened rollers 157, 157 carried upon the lower shaft 138, to trim off the apex portions of the successive blanks, as shown at 24, 24, Fig. 9, and also by the hatched portions of the blank 20a of Fig. 12.

In Fig. 2, the above described trimming and scoring devices are so positioned, relative to center line 21, on the rotary shafts 137, 138, as to obtain trimming and scoring operations appropriate to the passage of large size blanks, such as shown at 20, 20, Fig. 9. Figs. 11 and 12 show such trimming and scoring devices as adjusted inwardly on said shafts, toward the line 21, in positions appropriate to the passage of smaller blanks, of approximately the same size (see 20a, Fig. 9) as those produced by successive oblique cuts 19a of the narrow web 18a of Fig. 9. Said trimming and scoring devices carry any suitable means, such as set screws, not shown, for holding them in any desired positions of adjustment on the shafts 137, 138.

To facilitate such adjustments, the upper shaft 137, along with its scoring and trimming devices, is adapted to be raised, relative to the lower shaft 138. As shown in Figs. 11 and 13, the upper shaft 137 is rotatably mounted in blocks 158, 158 which are vertically slidably in openings 159, 159 of the side frame members 139 and 140. Above the shaft 137 is disposed a shaft 160, the ends of which are rotatably mounted in aligned apertures 161, 161 of members 162, 162 which bridge the openings 159, 159 of the side frame members 139 and 140. As

shown in Figs. 11 and 13, each bearing block 158 carries a substantially U-shaped member 163, whose upstanding arm portions at opposite sides of member 162, are apertured, as shown at 163', to receive eccentrically formed cam portions 164, 164 of the shaft 160. Between each pair of members 162, 163 is arranged a coil spring 165, thrusting downwardly on the associated block 158 to hold the shaft 137 in its lowermost or operative position. The shaft 160 carries a hand lever 165 by means of which the cams 164 are turned to raise slightly the blocks 158 and shaft 137, and thus give opportunity for endwise adjustments of the trimming and scoring devices toward or from line 21, to conform them to the selected size of the diamond-shaped pieces that are cut from the web material.

Adjustable mechanism for notching of blank edges

Following the scoring and trimming operations above described, each diamond-shaped piece is acted upon by mechanism which continues its movement in the direction of line 21 and which cuts suitable fold-defining notches (see 26 and 27, Fig. 9) in its leading and trailing edges at the opposite ends of each of its score lines 25, 25. Said mechanism, as shown in Figs. 1, 2, 15, 16, 17 and 18, includes two spaced parallel hollow shafts 166 and 167, both journalled at their ends in the side frames 139 and 140. Said shafts 166 and 167 are also centrally journalled in suitable bearings 166a (Fig. 16) carried by a central frame member 167a. To each said shaft is adjustably attached, as hereinafter described, a driving gear 168, both of said gears 168 being in mesh with an idler 169 of the gear train 39, which serves to rotate said shafts 166 and 167 in the same direction (counterclockwise in Fig. 1) as the preceding lower shaft 138 of the scoring and trimming mechanism.

Both of the shafts 166 and 167, adjacent to and on opposite sides of their central bearings 166a, are equipped with suitable blank-forwarding devices, which operate exclusively for the purpose of continuing each blank's movement in the direction of line 21. Such devices are the knurled forwarding rollers shown at 178, 178 on the shaft 166, and at 179, 179 on the shaft 167. Over such rollers pass only the central areas of each blank, i. e. the blank areas which in every case are disposed well inwardly of the several notch-cutting devices carried by said shafts.

For holding the blanks down in effective contact with said forwarding rollers 178 and 179, the mechanism provides suitable pairs of spring pressed upper rollers 176, 176 and 177, 177 respectively. Said upper rollers are carried by suitable brackets 176a and 177a (Fig. 18) attached to opposite sides of an overlying transverse bar 172 which is common to the two shafts 166 and 167. For the support of bar 172, the side frame 140 carries a suitable bracket 170, having a pin 171 (Fig. 16) on which the bar 172 is pivoted. The other end of bar 172 is received in a yoke member 173, pivoted at 174 to the other side frame 139. Said yoke member carries a screw 173a to which is attached a hand wheel 175 for moving said screw into and out of engagement with the free end of bar 172. Said bar 172 is thus normally held down in its illustrated operative position when the yoke member 173 occupies the vertical position shown in Fig. 16. When the screw 173a is backed off, allowing yoke 173 to be swung outwardly on its pivot 174, the bar 172 and parts carried thereby may be swung upwardly by means of an attached handle 172a, in order to give access, for adjustment purposes, to two pairs of sleeves 180, 180 on shaft 166, and 180a, 180a on shaft 167, which sleeves carry the angular cutters that produce the respective edge notches 26, 26 and 27, 27 of each forwardly moving blank.

On each of the sleeves 180a, 180a of Fig. 16 is shown the knife-edge cutter construction for producing the re-entrant notches 27, 27 of each blank's trailing edge; it will be understood that the similar cutter constructions on sleeves 180, 180 of shaft 166 are faced in the opposite direction (see Fig. 2), to cut the re-entrant notches 26, 26 of each blank's leading edge. Each sleeve 180 or 180a provides on its periphery (see Fig. 16) an angular or V-shaped knife edge 182, in adjacent relation to a slot 181 through the sleeve which communicates with the bore 185 of the associated shaft through an elongated opening 185' of the shaft wall. Each angular

knife edge 182 consists of a long outer leg 199, which is very nearly parallel with the associated shaft axis and short inner leg 201 at an angle to said axis. The two legs of each knife edge 182 meet at a point 200 (see Fig. 2), and the several sleeves are adjusted lengthwise of the shafts 166, 167 to register said points 200 with the score line locations (25) of the particular size of blank which is being handled. Thus the long legs 199 operate on the material of each blank's side flaps 28, 28 and the short legs operate on the material of its bottom and seal flaps 30 and 31 respectively.

For cooperation with these four angular knife edges 182, the mechanism provides corresponding overlying anvil rollers 183, having their spindles 183' mounted in suitable hangers 184. The latter, as shown in Fig. 17, are secured in pairs to brackets 198 which are adjustable lengthwise of the bar 172, in order to conform the anvil rollers 183 to the adjusted positions, on shafts 166 and 167, of their respective associated cutter sleeves 180, 180 and 180a, 180a. Ample leeway for such endwise adjustments of the cutter sleeves, while still maintaining their slots 181 in full communication with shaft openings 185', is afforded by the excess length of said shaft openings. Thus all of the elongated triangular chips, cut from each blank's leading and trailing edges by the four angular cutters 182 may be drawn by suction into and through the bores 185 of the shafts 166 and 167, each such bore for this purpose having a suitable connection 186 (see Fig. 2) with a source of vacuum, not shown, which operates continuously to obtain such waste or chip disposal.

By the above-described adjustments of sleeves 180 and 180a, toward and from the line 21, the notching mechanism is able to take care of all variations in the lengthwise dimensions of the diamond-shaped blanks. Furthermore, all variations in the widthwise dimensions of such blanks (i. e., varying distances between their leading and trailing edges) are taken care of without disturbing communication between sleeve openings 181 and shaft openings 185'. As shown in Figs. 15 and 16, each shaft 166, 167 is connected to its driving gear 168 through an interiorly-tapered sleeve 202, to which the gear is pinned, as shown at 202a. Each sleeve 202 is received on a correspondingly tapered shaft portion 203 beyond the gear, and held fast thereto by a suitable nut 204 on the end of the shaft. When said nut is backed off, the shaft (166 or 167) with its notching cutter parts, can be turned within the gear 168 to any required angular setting, following which the nut 204 is tightened to re-establish the driving connection between gear and shaft.

I claim:

1. In an envelope machine, mechanism for producing different sizes of substantially diamond-shaped envelope blanks from different widths of paper webs forwarded therethrough, said mechanism comprising, means for continuously advancing a paper web, means for adjusting a web widthwise of itself so that any web irrespective of its width will be advanced through the mechanism with one marginal edge portion thereof coinciding with a predetermined path, knife means for successively severing the web obliquely, thereby to form separate unconnected diamond-shaped pieces, means for advancing said pieces in a fixed path which diverges at an angle from the web path, and means for angularly adjusting said knife means and said web advancing means independently in relation to said fixed path about a common vertical axis in said fixed path's centerline which is intersected by the predetermined path of said edge portion of the web, thereby to obtain advancement of the severed pieces along said fixed path in symmetrical relation to said centerline regardless of differences in the size of said pieces.

2. In mechanism of the class described, means for feeding web material, means for severing such material transversely to produce successive substantially diamond-shaped blanks, for manufacture into envelopes by movement in a fixed path which diverges from the web path, said feeding means and said severing means being angularly adjustable, independently, about a common vertical axis in the centerline of said fixed path, to adapt them to different width webs in the production of different sizes of blanks, and means for maintaining one marginal edge of the web material in intersecting relation to said axis.

3. In the production of substantially diamond-shaped

envelope blanks, by successive oblique cutoffs of paper web material whose feed is at an angle to a fixed path of movement for said blanks, the improvement which consists in adjusting the obliquity of the cut and the direction of web feed independently, about a common vertical axis in the centerline of said fixed path, for the handling of different widths of webs in producing different sizes of blanks, and maintaining in each position of web feed the intersection of the web's marginal edge with said axis.

4. In the production of substantially diamond-shaped blanks, by successive transverse cuts of a continuously fed paper web, the improvement which consists in adjusting the obliquity of the cut and the direction of web feed independently, but about the same vertical axis, for the handling of different widths of webs in producing different sizes of blanks, and maintaining for each web, regardless of width, an intersecting relation between one marginal edge thereof and said vertical axis.

5. In mechanism of the class described, means for continuously feeding paper web material, cutting means at an angle to the direction of web feed and operable on each web to produce a succession of substantially diamond-shaped blanks, means for adjusting the obliquity of said cutting means and the direction of web feed about a common vertical axis, to adapt said mechanism to the handling of different width webs in the production of different sizes of substantially diamond-shaped blanks, and means for maintaining a marginal edge of each web so handled in intersecting relation to said axis.

6. In mechanism of the class described, means for continuously feeding paper web material, means for successively cutting, obliquely, such a web's advancing end, to produce substantially diamond-shaped envelope blanks, means for forwarding said blanks in a fixed direction at an angle to the direction of web feed, pivotal supports on a common vertical axis in the centerline of said fixed direction for said web feeding and web cutting means, to permit of angular adjustments, in web feed direction and obliquity of cut, as required by different widths of webs in the production of different sizes of substantially diamond-shaped blanks and means for laterally adjusting each web, to position its proximate edge in intersecting relation to said vertical axis, whereby the cut off blanks, regardless of size, are disposed in symmetrical relation to said centerline.

7. In mechanism of the class described, means for continuously feeding paper web material, means for successively cutting, obliquely, such a web's advancing end, to produce substantially diamond-shaped envelope blanks, means for forwarding said blanks in a fixed direction at an angle to the direction of web feed, pivotal supports on a common axis for said web feeding and web cutting means, to permit of angular adjustments, in web feed direction and obliquity of cut, as required by different widths of webs in the production of different lengths of substantially diamond-shaped blanks, means for varying the speed of web feed, to adapt said mechanism to the production of blanks of different widths, and means for laterally adjusting each web, to position its proximate edge in intersecting relation to said axis, whereby the cut off blanks, regardless of size, are disposed in symmetrical relation to the fixed direction imparted thereto by said forwarding means.

8. In mechanism of the class described, means for continuously feeding paper web material, means for successively cutting, obliquely, such a web's advancing end, to produce substantially diamond-shaped envelope blanks, pivotal supports on a common axis perpendicular to the centerline of said blanks' further advance for said web feeding and web cutting means, to permit of angular adjustments, in web feed direction and obliquity of cut, as required by different widths of webs in the production of different sizes of substantially diamond-shaped blanks, and means for maintaining an edge of each web so operated upon, in intersecting relation to said axis.

9. In mechanism of the class described, means for continuously feeding paper web material, means for successively cutting, obliquely, such a web's advancing end, to produce substantially diamond-shaped envelope blanks, pivotal supports on a common axis for said web feeding and web cutting means, to permit of angular adjustments, in web feed direction and obliquity of cut, as required by different widths of webs in the production of different

sizes of substantially diamond-shaped blanks, means for changing the speed of web feed, in accordance with such requirements, and means for maintaining an edge of each web so operated upon, in intersecting relation to said axis.

5 10 15 20 25 30 35 40 45 50 55 60 65 70 75 80 85

10. In the production of substantially diamond-shaped envelope blanks of various sizes by successive oblique cuts of continuously-fed paper web material of different widths, the improvement which consists in angularly adjusting the obliquity of the cut and the direction of web feed, both with reference to a fixed direction of feed for the severed blanks, and both about a common vertical axis, and maintaining for each web, regardless of its width, an intersecting relation of its proximate marginal edge with said axis, whereby the cut off blanks, regardless of size, are disposed symmetrically, in relation to their fixed direction of subsequent feed.

11. In the production of substantially diamond-shaped envelope blanks of various sizes from continuously-fed paper web material of different widths, the improvement which consists in making successive oblique cuts of said web material to produce diamond-shaped pieces, angularly adjusting the obliquity of the cut and the direction of web feed, both with reference to a fixed direction of feed for the severed pieces, and both about a common vertical axis, maintaining for each web, regardless of its width, an intersecting relation of its proximate marginal edge with said axis, whereby the cut off pieces, regardless of size, are disposed symmetrically, in relation to their fixed direction of subsequent feed, and trimming, scoring, and notching said pieces, to convert them into envelope blanks during their movement in symmetrical relation to said fixed direction of blank feed.

12. In mechanism of the class described, means for feeding web material, means for severing such material obliquely to produce successive substantially diamond-shaped envelope blanks, means for forwarding said blanks in a fixed direction at an angle to the direction of web feed, means for angularly adjusting said web feeding means and said web severing means both with reference to said fixed direction of blank feed and both about a common vertical axis, to adapt them to different width webs in the production of different sizes of blanks, and means for laterally adjusting each web to dispose its proximate marginal edge in intersecting relation to said axis, whereby said cut off blanks, regardless of size, are disposed in symmetrical relation to said fixed direction of blank feed.

13. In the production of substantially diamond-shaped envelope blanks of various sizes from continuously-fed paper web material of different widths, the improvement which consists in making successive oblique cuts of said web material to produce diamond-shaped pieces, angularly adjusting the obliquity of the cut and the direction of web feed, both with reference to a fixed direction of subsequent feed for the severed pieces, and both about a common vertical axis, trimming and notching said severed pieces during their feed in said fixed direction, maintaining for each web, regardless of its width, an intersecting relation of its proximate marginal edge with said axis, whereby the severed pieces, regardless of size, are disposed symmetrically, in relation to their fixed direction of subsequent feed, and adjusting the trimming and notching devices to the size of the so-severed and so-fed pieces.

14. In the production of substantially diamond-shaped envelope blanks of various sizes from continuously-fed paper web material of different widths, the improvement which consists in making successive oblique cuts of said web material to produce diamond-shaped pieces, angularly adjusting the obliquity of the cut and the direction of web feed, both with reference to a fixed direction of subsequent feed for the severed pieces, and both about a common vertical axis, trimming and notching said severed pieces during their feed in said fixed direction, maintaining for each web, regardless of its width, an intersecting relation of its proximate marginal edge with said axis, whereby the severed pieces, regardless of size, are disposed symmetrically, in relation to their fixed direction of subsequent feed, adjusting the trimming and notching devices transversely of said fixed direction, to conform them to the length of the severed pieces, and adjusting the notching devices angularly, to conform them to the width of the severed pieces.

15. In the production of substantially diamond-shaped envelope blanks of various sizes from continuously-fed paper web material of different widths, the improvement which consists in making successive oblique cuts of said web material to produce diamond-shaped pieces, angularly adjusting the obliquity of the cut and the direction of web feed, both with reference to a fixed direction of subsequent feed for the severed pieces, and both about a common vertical axis in the centerline of said fixed subsequent feed direction, maintaining for each web, regardless of its width, an intersecting relation of its proximate marginal edge with said axis, whereby the severed pieces, regardless of size, are disposed symmetrically in relation to the center line of their fixed direction of subsequent feed, and finally trimming and notching said severed pieces while moving in said fixed direction, at distances on opposite sides of said center line that are in conformity with the size of said pieces.

16. In mechanism of the class described, means for feeding web material, means for severing such material obliquely to produce successive diamond-shaped pieces for formation into envelope blanks, means for feeding the severed pieces in a fixed direction at an angle to the direction of web feed, means for trimming and notching said pieces, while being fed in such fixed direction, means for angularly adjusting the web feeding means about a substantially vertical axis in the centerline of said fixed direction, means for angularly adjusting the web severing means about a substantially vertical axis in said centerline, means for laterally adjusting each web to dispose an edge thereof in intersecting relation to said last-mentioned axis, and means for adjusting said trimming and notching means, transversely in relation to the centerline of said fixed direction of feed, to accommodate same to the production of different sizes of substantially diamond-shaped envelope blanks.

17. In mechanism of the class described, means for feeding web material, means for severing such material obliquely to produce successive diamond-shaped pieces for formation into envelope blanks, means for forwarding said pieces in a fixed direction at an angle to the direction of web feed, blank trimming and notching devices for operation on said pieces while the latter are being fed in said fixed direction, means for angularly adjusting said web feeding means and said web severing means both with reference to said fixed direction of blank feed and both about a common vertical axis, to adapt said means to different width webs in the production of different sizes of pieces, means for laterally adjusting each web to dispose its proximate marginal edge in intersecting relation to said axis, whereby said cut off pieces, regardless of size, are disposed in symmetrical relation to said fixed direction of blank feed, and means for adjusting said blank trimming and notching devices transversely in relation to said fixed direction of blank feed, to accommodate them to the production of different lengths of said substantially diamond-shaped envelope blanks.

18. In mechanism of the class described, means for feeding web material, means for severing such material obliquely to produce successive diamond-shaped pieces for formation into envelope blanks, means for forwarding

- said pieces in a fixed direction at an angle to the direction of web feed, blank trimming and notching devices for operation on said pieces while the latter are being fed in said fixed direction, means for angularly adjusting said web feeding means and said web severing means both with reference to said fixed direction of blank feed and both about a common vertical axis, to adapt said means to different width webs in the production of different sizes of pieces, means for laterally adjusting each web to dispose its proximate marginal edge in intersecting relation to said axis, whereby said cut off pieces, regardless of size, are disposed in symmetrical relation to said fixed direction of blank feed, means for adjusting said blank trimming and notching devices transversely in relation to said fixed direction of blank feed, to accommodate them to different lengths of said diamond-shaped pieces, and means for adjusting said notching devices angularly, to accommodate them to different widths of said diamond-shaped pieces.
19. In mechanism of the class described, means for feeding web material, means for severing such material obliquely to produce diamond-shaped pieces for formation into envelope blanks, means for feeding the successively severed pieces in a fixed direction at an angle to the direction of web feed, devices operable on each piece while moving in said fixed direction for cutting re-entrant corner-defining notches in its leading and trailing edges, means for adjusting said web feeding means and said web severing means, angularly in relation to said fixed direction and about a vertical axis which is intersected by an edge of each web, to adapt said mechanism to the production of different lengths and widths of said diamond-shaped pieces, means for adjusting said notch-cutting devices transversely in relation to said fixed direction of feed, to accommodate them to the production of different lengths of substantially diamond-shaped envelope blanks, and means for adjusting said devices angularly in relation to each other, to accommodate them to the production of different widths of substantially diamond-shaped envelope blanks.
